[57] CLAIM

The ornamental design for a pet carrier, as shown and described.

DESCRIPTION

FIG. 1 is a perspective view of a pet carrier showing my new design;

FIG. 2 is a front elevational view thereof;

FIG. 3 is a left side elevational view thereof; the right side elevational view being a mirror image thereof;

FIG. 4 is a rear elevational view thereof;

FIG. 5 is a top plan view thereof; and,

FIG. 6 is a bottom plan view thereof.

FIGS. 2-6 are drawn in an enlarged scale. The broken line showing of an animal is for illustrative purpose only and forms no part of the claim. Other broken lines represent stitch lines.
